SOAP CONTAINER

Erskine K. Bludworth, Dallas, Tex.

Application October 8, 1945, Serial No. 620,945

4 Claims. (Cl. 45—28)

1

The present invention relates to soap containers of a sectional box type, the box being adapted to contain a conventional bar of soap, and there being a tray for the soap on the interior of the box, the tray being swung automatically to elevated position when the lid of the box is lifted, and the purpose of the instant invention is to structurally, functionally, and otherwise improve upon known types of containers in this same category.

Generally speaking, the present invention is in the form of a box or container constructed in a manner to facilitate the removal of the soap therefrom, provision being made to prevent sticking or adhering of the soap to any part of the box, or, in the event of any such tendency to stick or adhere to the box, and, secondly, the soap will be loosened incidental to the opening of the box for bodily removing the soap therefrom.

More specifically, the invention pertains to a box-like container having a lid hinged to one longitudinal side thereof adapted to be opened and closed in a customary fashion, there being a raised platform in the bottom of the container proportionately smaller than said container and centered therein in relation to the upstanding marginal rim, this for supporting a bar of soap. A tray is arranged in the container and the tray is larger than the platform and provided with an apertured bottom which fits around the platform, said platform then serving as a false bottom and also to support the bar of soap, whereby removal of the tray out of the container, which is accomplished automatically with the opening of the lid, said bar of soap, remaining in said tray, will be lifted to an elevated usable position.

Added novelty resides in the provision of connecting links between the ends of the tray and the ends of said raised platform, the lid having actuating arms or members rigidly connected to its rim portion and said members having operating connections with adjacent portions of said tray.

The invention, together with its objects and advantages, will be best understood from a study of the following description taken in connection with the accompanying drawings, wherein:

Figure 1 is a perspective view of a soap box embodying the features of the present invention, the same being shown in fully closed position.

Figure 2 is a top plan view of the soap box in fully open position.

2

Figure 3 is an end elevational view of the soap box in fully open position.

Figure 4 is a transverse sectional view through the soap box in fully open position, this on line 4—4 of Figure 2.

Figure 5 is a transverse sectional view through the soap box in fully closed position, this on the approximate line 5—5 of Figure 1.

Referring more in detail to the drawings, it will be seen that the box, which may be made from sheet metal or any other suitable material, embodies a box or container part 5 having hinged thereto, as at 6, a cover or lid 7.

In accordance with the present invention, the box 5 is provided in the bottom thereof, and spaced from the peripheral walls of the box, a raised formation or platform 8 that serves as a false bottom for a tray 9.

The tray 9 is provided, at the bottom or underside thereof, with apertured lugs 10 in which are journaled the pintle ends 11 of links or arms 12 that also have pintle ends 13 journaled in apertures provided therefor in the flange 8a of the platform or support 8 at opposite ends of the latter.

The rim of the tray 9, at opposite ends thereof, is provided with suitable openings 14 in which are loosely engaged the angular or hook-like ends 15 of rigid arms 16 that at one end are welded or otherwise permanently secured interiorly of the lid 7 to the flange of the lid 7 at opposite ends of said lid as shown.

Preferably the lugs 10 are formed by being struck out from the bottom of the tray 9 as best shown in Figure 2, and the lid 7 is arranged to close down onto a peripheral enlargement or shoulder 17 of the box or container part 5 in a well-known manner.

Any suitable form of fastening means may be resorted to for retaining the lid or closure 7 in closed position.

The bottom 18 of the tray 9 is provided with an opening 19 that is slightly larger than the over-all dimensions of the raised formation or platform 8 so as to accommodate said raised formation or platform 8 when the box is closed and the tray 9 is thereby positioned within the container 5 as shown to advantage in Figure 5.

With the parts as shown in Figure 5, the platform or raised formation 8 serves as a continuation of the bottom 18 of tray 9 and cooperates therewith in supporting the soap within the tray.

As is apparent, the tray 9 moves when the lid 7 is moved. Consequently, when the lid 7 is moved to open position, the tray 9 moves upwardly and

outwardly from the box 5 carrying with it the soap that may then be readily removed from the tray 9.

It is believed that the many advantages of a soap box embodying the features of the present invention will be had by those skilled in the art and from the foregoing without further detailed description.

It will also be understood that while I have herein stated the box to be particularly designed for carrying soap, it is apparent that it may also be used for holding other articles.

Accordingly, while I have herein illustrated and described what is considered the preferred embodiment of the invention, I am well aware that in practical fields of use minor changes may be made therein without departing from the spirit of the invention as hereinafter claimed.

This application for Letters Patent is based on an application for corresponding subject matter heretofore identified as Serial No. 406,544 and filed August 12, 1941, and allowed September 23, 1942. Said application became duly forfeited and then abandoned for want of proper action.

Having thus described the invention, what is claimed as new is:

1. A box for soap, or the like, comprising a container, a lid for said container hinged to one side thereof for opening and closing movement, a raised platform in the bottom of the container relatively smaller than said container and centered therein for supporting a bar of soap, a tray fitting in said container, said tray being larger than said platform and provided with an apertured bottom fitting around said platform and forming a soap bar supporting extension thereof, whereby removal of the tray out of the container will cause the same to lift said bar off said platform, and means to move said tray upwardly out of said container under opening movement of said lid.

2. A box for soap, or the like, comprising a container, a lid for said container hinged to one side thereof for opening and closing movement, a raised platform in the bottom of the container relatively smaller than said container and centered therein for supporting a bar of soap, a tray fitting in said container, said tray being larger than said platform and provided with an apertured bottom fitting around said platform and forming a soap bar supporting extension thereof, whereby removal of the tray out of the container will cause the same to lift said bar off said platform, and means to move said tray upwardly out

of said container under opening movement of said lid, said means comprising a pair of arms fixed at corresponding ends thereof to said lid and pivotally connected at the other ends thereof to opposite sides of said tray, respectively.

3. A box for soap or the like comprising a container, a lid for said container hinged to one side of the latter for opening and closing movements, a raised platform in the bottom of the container relatively smaller than said container and centered therein for supporting a bar of soap, a tray fitting in said container, said tray being larger than said platform and provided with an apertured bottom fitting around the perimeter portion of said platform, said tray being adapted to accommodate the soap bar and said platform constituting a false bottom when the tray is in its lowermost position, rigid arms connected to and projecting beyond the rim portions of said lid, the free ends of said arms being formed into hook-like terminals, there being openings formed in the opposite end portions of the rim of said tray, said hook-like terminals fitting into said openings, whereby, when the lid is swung open, the tray is lifted up and away from said platform, and assembling and retaining means connecting the tray with said platform.

4. A box for soap or the like comprising a container, a lid for said container hinged to one side thereof for opening and closing movements, a raised platform in the bottom of the container relatively smaller than said container and centered therein for supporting a bar of soap, a tray fitting in said container, said tray being larger than said platform and provided with an apertured bottom fitting around the perimeter portion of said platform, said tray being adapted to accommodate the soap bar and said platform constituting a false bottom when the tray is in its lowermost position, rigid arms connected to and projecting beyond the rim portions of said lid, the free ends of said arms being formed into hook-like terminals, and openings formed in the opposite end portions of the rim of said tray, said hook-like terminals fitting into said openings, whereby, when the lid is swung open, the tray is lifted up and away from said platform, together with links, said links being connected at corresponding ends to the end portions of said raised platform, the opposite end of said links being hingedly connected with adjacent portions on the bottom of said tray.

ERSKINE K. BLUDWORTH.
